UNITED STATES PATENT OFFICE

2,454,939

COIN AND DISK PROJECTOR FOR
AMUSEMENT DEVICES

Raymond S. Oakes, Brookfield, III.

Application April 11, 1946, Serial No. 661,428

3 Claims. (Cl. 273—129)

1

The invention relates to amusement devices and more particularly to a coin propelling device used in connection with amusement devices.

It is an object of the invention to provide a coin chute for amusement devices permitting a coin to be propelled onto a field.

It is a further object to provide a coin chute movably secured to an amusement device and adapted to be manipulated so as to vary the path of the propelled coin.

A still further object constitutes the provision of a coin chute secured for universal movement to an amusement device.

It is also an object of the invention to provide certain features of construction and arrangement of parts tending to enhance the efficiency and utility of a device of the character specified.

With these and other objects in view which will become more apparent from a perusal of the invention, the latter comprises the means described in the specification particularly pointed out in the claims forming a part thereof, and illustrated in the accompanying drawing, in which

Fig. 1 is a top plan view of an amusement device to which my invention has been applied.

Fig. 2 is a section on the line 2—2 of Fig. 1.

Fig. 3 is an enlarged section on the line 3—3 of Fig. 1.

Fig. 4 is a section on the line 4—4 of Fig. 3.

Fig. 5 is a top plan view of the coin tossing device.

Fig. 6 is a detail section on the line 6—6 of Fig. 3, and

Fig. 7 is a detail section on the line 7—7 of Fig. 3.

Referring to the several views of the drawing 10 generally designates an amusement device in the form of a box comprising a front wall 11, side walls 12 and a rear wall 13.

A partition 14 is inserted in horizontal grooves 15 in the rear and side wall and rests on the upper edge of the front wall so as to occupy a horizontal position. A glass plate 16 likewise extends into grooves 17 of the rear and side walls and forms a top closure for the device. The front end of the glass plate 16 is secured to a panel board 18 rising medially from the front wall to complete the front closure of the box. The partition 14 is provided at forward end with a centrally located semi-circular extension 19 extending beyond the front wall of the box.

The partition 14 forms the playing field and is provided with intersecting lines 20 and 21 defining squares which along one longitudinal and

transverse edge may be serially numbered for the purpose of identification.

At the center of the field four openings 22 are provided in the partition for permitting coins to drop therethrough.

A bottom 23 defines a chamber 24 in the box and constitutes a repository for coins falling through the openings 22.

Pegs 25 are provided at the corner of the squares and form obstacles in the path of coins propelled into the box.

The device heretofore described per se does not form the invention and is merely described by way of example as one form of amusement device to which my invention may be applied.

In order to control the propelling of a coin, I provide a novel coin chute which permits variations of the trajectory of the moving coin.

The coin chute comprises two plates 26 spaced sufficiently apart for the passage of a coin or other flat object and provided with a filler piece 27 at the bottom which tapers at the top from the outer end downwardly toward the inner end to afford a slanting runway 28.

The plates 26 are secured together with rivets 29 and the coin passage is closed on the top by a cover 30 which extends beyond the inner end of the plates 26 to form an arcuate lip 31.

The plates 26 are inserted in a rectangular slot 32 of a cylindrical member or drum 33. The slot 32 extends through the member 33 to communicate with the interior of the amusement device and forms the continuation of the coin passage defined by the plates 26. The slot 32 originates at the top of the member 33 and extends downwardly to a point short of the lower end to provide a bottom 34.

A circular cover plate 35 is secured to the top of the member 33 by a pair of screws 26, the plate 35 being cut away as at 37.

The plates 26 have registering apertures 38 to receive set screws 39 which pass through bores 40 in the cylindrical member 33. The set screws 39 constitute a pivot for the plates 26 which may be swung vertically, the cut-away portion of the cover plate 35 permitting an appreciable range of movement.

The cylindrical member 33 is provided in its bottom plate with a countersunk central opening 41 in which is received the head 42 of a wood screw 43.

The front panel 18 is cut away to provide clearance for the cylindrical member 33 and the wood-screw 43 is screwed into the front wall. It is evident that the coin chute may be turned hori-

zontally through a wide range about the screw 43 and may be elevated about the pivot 39 so as to impart different propelling forces to the coin and consequently cause the coin to come to rest anywhere on the playing field of partition 14 or drop through the openings 22 into the repository.

The pegs 25 constitute obstacles and enhance the enjoyability of the game by requiring considerable skill to propel the coin to a remote square on the field.

While the drawing shows one embodiment of the invention, numerous changes and alterations may be made without departing from the spirit of the invention. I, therefore, do not limit myself to details of construction and arrangement of parts, as shown, but include all modifications and variations constituting departures within the scope of the invention as defined in the appended claims.

I claim:

1. As an article of manufacture, a coin propelling device comprising a drum provided with a through slot, means for supporting said drum for rotation about a vertical axis, and a coin chute having a slanting runway secured at one end in said slot for pivotal movement about a horizontal axis intersecting said vertical axis.

2. For use with an amusement apparatus, a coin propelling device comprising a drum provided with a through slot communicating with

the interior of the apparatus, and a coin chute having a slanting runway secured at one end in said slot for vertical pivotal movement.

3. For use with an amusement apparatus, a coin propelling device comprising a drum provided with a through slot communicating with the interior of the apparatus, means for supporting said drum for rotation about a vertical axis, and a coin chute having a slanting runway secured at one end in said slot for pivotal movement about a horizontal axis.

RAYMOND S. OAKES.
